APPARATUS FOR DRY SUMP LUBRICATION
OF ENGINESErnest A. Mori, Pittsburgh, Pa., assignor to Gulf
Research & Development Company, Pittsburgh,
Pa., a corporation of Delaware

Application October 12, 1945, Serial No. 621,886

5 Claims. (Cl. 184—6)

1

This invention relates to improvements in engine lubrication systems of the dry sump type. These are so called because the oil supply, instead of being retained in the crankcase as in conventional automobile engines, is contained in a separate tank from which it is pumped to the engine, and thence is continuously returned to the supply tank as rapidly as it drains into the crankcase. Inasmuch as the crankcase is substantially dry at all times the engine is not susceptible to flooding and fouling when operating in tilted positions, whereas engines of conventional type in which the oil supply is self-contained must operate in horizontal position, or one not departing greatly from horizontal, to avoid such effects. Engines embodying dry sump lubrication, therefore, have especial utility in the field of aviation because they do not impose limitations on the maneuverability of an airplane.

In order to withdraw the oil normally draining to the crank case, as well as to accommodate the sudden surges tending to overrun the sump, the scavenging pump is designed with a capacity of at least $2\frac{1}{4}$ times the normal oil requirement of the engine. Fluctuating drainage of oil into the sump may be due to any or all of several causes, such as variations in engine speed, maneuvering of the airplane which requires the engine to assume changing positions and inclinations, and by intermittent actuation of hydraulic control devices drawing their supply of fluid from the engine lubrication system, as for example mechanisms for changing propeller pitch. Thus, since the scavenging pump must be designed with a capacity sufficient to keep the oil in the sump at a low level under all operating conditions, the pump intake will at times be partly or wholly uncovered. As a result the scavenging pump sucks air or gas along with the oil during a considerable period of its operation, and the air becomes mechanically entrained in the oil returned to the supply tank, due in part to the beater action of the pump on the oil-air mixture. This presents a hazardous condition, for at high altitudes the entrained air bubbles expand in the intake side of the pressure pump supplying oil to the engine due to the high ratio of absolute pressure in the oil supply tank to the absolute pressure in the pump gear teeth. At high altitudes the flow of oil to the engine is reduced to the danger point or below, depending upon the amount of air entrainment, since the oil delivery of the pressure pump is reduced

in proportion to the volume of air present in the gear teeth.

Various expedients have been adopted to minimize or avoid air entrainment in the lubricating oil, mainly by mechanical means such as arrangements of baffles and compartments in the supply tank which permit the bubbles to separate from the body of oil. Another solution, and one of much practical value, is disclosed in the patent to Bruce R. Walsh, No. 2,373,360. This comprises a main scavenging pump drawing from the bottom of the sump and of a capacity sufficient to keep the oil therein at a low level under normal conditions, yet with its intake always submerged, and an auxiliary scavenging pump drawing from a higher level, above the normal one, and separately delivering to the upper part of the supply tank. Thus, the main scavenging pump handles only oil, regardless of variations in the amount of oil draining to the crankcase, and the auxiliary scavenging pump normally discharges air through a separate pipe into the supply tank above the oil level therein so that the air is vented to atmosphere without mixing with the oil, yet upon undue rise of oil in the sump the auxiliary pump is primed and assists in discharging excess oil back to the supply tank to return the sump level to normal.

Such a system requires separate lines of piping between the main and auxiliary scavenging pumps, respectively, and the oil supply tank. Military necessity dictates that the amount of piping be reduced to minimize the chance that this vital part of the operating mechanism of an airplane might be punctured by a bullet, and in both military and civilian use it is desirable to eliminate, in so far as possible, a multiplicity of pipes which, if they should break, could cause a complete failure of engine lubrication with disastrous consequences.

It is accordingly one of the principal objects of my invention to provide a dry sump lubrication system which incorporates main and auxiliary scavenging pumps both of which deliver to an oil supply tank through the same pipe, yet without entraining air in the oil so delivered, irrespective of a fluctuating oil level in the sump.

Other and further objects will be evident from the following description and drawings, in which:

50 Figure 1 is a partly diagrammatic view of one form of my invention embodying main and auxiliary scavenging pumps, and pressure pump, in line.

55 Figure 2 is also a partly diagrammatic view of a modified arrangement wherein the main

scavenger pump is mounted inside the engine crankcase and is driven by a shaft geared to the main drive shaft for the auxiliary scavenger pump and the pressure pump.

Referring more particularly to the drawings and first to Figure 1 thereof, an engine crankcase 10 is provided with a sump 11 in its bottom to receive oil draining from the engine bearings. The oil for lubrication is delivered from tank 12, through pipe 13 and pressure pump 14, and thence through pipe 15 to the engine. A main scavenger pump 16 and an auxiliary scavenger pump 17 are mounted in line with the pressure pump 14, and all are directly driven by shaft 18 which projects through the crankcase. The inlet pipe 19 of the main scavenger pump extends into sump 11 at a low point, below the normal oil level 20 whereas the inlet pipe 21 of the auxiliary scavenger pump terminates in the sump above the normal level, as indicated at 22.

The main scavenger pump discharges through pipe 23 and through either the upper or lower branch pipes 24 and 25 to the top or bottom of the supply tank, depending upon the position of the two-way valve 26. Thus, during the warm-up period for the engine, oil returned to the supply tank may be directed through the lower branch pipe 25 which enters the tank closely adjacent to the inlet of pipe 13, whereby more direct circulation of the warm oil is obtained. Following the initial warm-up period it is usually desirable to adjust valve 26 so that oil returning to the supply tank flows through the upper branch 24 where heat may be extracted by a heat exchange cooler 27 prior to its discharge into the tank over the curved surface of baffle 28 which assists in eliminating any air bubbles from the sheet of oil flowing thereover, and avoids agitation of the main body of oil such as would cause bubbles of air to form in it.

At extremely high altitudes the effect of the cooler 27 might so increase the viscosity of the oil as to retard free flow, in which event relief valve 29 will open and permit the oil to take an alternative path by-passing the cooler.

Any sudden surge of oil collecting in the sump and tending to overrun it is drawn by pipe 21 into the auxiliary scavenger pump and discharged through the branch pipe 30 into the stream from the main scavenger pump. When this occurs the single pipe 23 serves both main and auxiliary scavenger pumps. Normally, however, since the inlet of the auxiliary scavenger pump is entirely uncovered it will pump only air. For reasons heretofore pointed out it is undesirable to mix air with the main oil stream. My invention, therefore, provides a spring-pressed check valve 31 of two or three pounds pressure in the branch pipe 30, and a restricted bleeder tube 32 between the auxiliary scavenger pump and check valve, and desirably near the check valve, leading back into the crankcase. So long as the intake of the auxiliary scavenger pump is uncovered, air which is pumped will merely be discharged back to the crankcase through the bleeder tube, since its pressure will be insufficient to overcome the pressure of oil behind the check valve plus the spring pressure tending to hold the valve closed. If the oil should rise in the sump to the level 22, or higher, the auxiliary scavenger pump will immediately prime itself because of the air bleed in the discharge side, and thereupon the check valve will open so that the auxiliary oil stream will join the main one but will be discontinued abruptly when a low level is restored in the sump.

The assembly of Figure 2 is similar in its operation. Here, however, the main scavenger pump 33 is mounted inside the crankcase and is driven by a short shaft 34 connected to the drive shaft 35 by bevel gearing 36. As in the previously described embodiment, the main scavenger pump discharges through a pipe 37 to a supply tank 38, through either an upper branch 39 or a lower branch 40, controlled by a two-way valve 41. Here, also, the upper branch has a cooler 42 and valve controlled by-pass 43, while the lower branch entering the tank opens adjacent to the pipe 44 which supplies the pressure pump 45.

The connection between the auxiliary scavenger pump 46 and the main oil line, as shown, comprises a short connecting pipe 47 in which a spring pressed check valve 48 is mounted and which normally closes the passage. Thus, when the intake pipe 49 of the auxiliary scavenger pump is uncovered, air which is pumped cannot enter the main supply pipe and therefore passes back to the crankcase through a small bleeder tube 50 which communicates with the pipe 47 between the auxiliary scavenger pump and the check valve. When the oil in the sump rises sufficiently, to be picked up by the auxiliary scavenger pump, however, the check valve will open under the increased pressure exerted on it and the auxiliary oil stream will thereupon join the main stream as the same is discharged by the main scavenger pump. In both this and the preceding embodiment it is to be noted that the bleeder tube is of such small bore that although air is effectively vented back to the crankcase, only a negligible amount of oil can return by this route, due to greater resistance to the passage of the more viscous liquid, so that this discharge of oil from the auxiliary scavenger pump into the main oil stream is not appreciably reduced.

What I claim is:

1. A dry sump lubrication system for engines comprising an oil supply tank separate from the engine and a pressure pump delivering oil therefrom to the engine, a main scavenger pump having an inlet which is submerged in oil retained in the engine sump, an auxiliary scavenger pump having an inlet which is normally above the level of oil in the sump, a common discharge pipe for both the main and auxiliary scavenger pumps leading to said supply tank, a valved connection between the discharge of said auxiliary scavenger pump and said common discharge pipe, and means for bleeding off air which is normally pumped by said auxiliary scavenger pump.

2. A dry sump lubrication system for engines comprising an oil supply tank separate from the engine and a pressure pump delivering oil therefrom to the engine, a main scavenger pump having an inlet which is submerged in oil retained in the engine sump, an auxiliary scavenger pump having an inlet which is normally above the level of oil in the sump, a common discharge pipe for both the main and auxiliary scavenger pumps leading to said supply tank, a valved connection between the discharge of said auxiliary scavenger pump and said common discharge pipe normally closing communication therebetween when said auxiliary scavenger pump discharges air but adapted to establish communication therebetween when oil is pumped, and bleeder means for relieving air pumped by the auxiliary scavenger pump when the valved connection closes communication with the common discharge pipe.

3. In a dry sump lubrication system including main and auxiliary scavenger pumps drawing from

different levels in the engine crankcase and discharging to a separate supply tank, and a pressure pump returning oil from the supply tank to the engine, the improvement comprising a common discharge pipe for both the main and auxiliary scavenge pumps leading to said supply tank, a valved connection between the discharge of said auxiliary scavenge pump and said common discharge pipe adapted to establish communication therebetween only when oil is being delivered by said auxiliary scavenge pump, and a bleeder for air pumped by said auxiliary scavenge pump when communication with said common discharge pipe is blocked.

4. A dry sump lubrication system for engines comprising an oil supply tank separate from the engine and a pressure pump delivering oil therefrom to the engine, a main scavenge pump drawing oil from the engine crankcase at a low point therein, an auxiliary scavenge pump drawing from a higher level normally above any accumulation of oil in the crankcase, a common discharge pipe for said main and auxiliary scavenge pumps communicating with said supply tank, a connecting pipe between the outlet of said auxiliary scavenge pump and said common discharge pipe, a check valve therein adapted to open under pressure of liquid discharged by said auxiliary scavenge pump and a bleeder tube communicating with said connecting pipe between the outlet of said auxiliary scavenge pump and said check valve.

5. A dry sump lubrication system for engines comprising an oil supply tank separate from the engine and a pressure pump delivering oil therefrom to the engine, a main scavenge pump drawing oil from a sump in the engine crankcase and having an inlet which is continuously submerged, an auxiliary scavenge pump drawing from a higher level, normally above the oil level in the

sump, a common discharge pipe for both the main and auxiliary scavenge pumps leading to said supply tank, a connection between the discharge of said auxiliary scavenge pump and the said common discharge pipe, a spring-pressed check valve in said connection, said check valve being normally closed when air is discharged by said auxiliary scavenge pump, and means providing a restricted passage extending from said connection at a point adjacent said check valve at the upstream side thereof to relieve air discharged from said auxiliary pump during normal operation, said check valve opening and establishing communication between said auxiliary scavenge pump and common discharge pipe at such times as the inlet of the auxiliary scavenge pump becomes submerged in oil and the auxiliary scavenge pump primes itself due to the presence of the restricted passage between the pump and check valve through which passage the pump can exhaust the air entrapped in its pumping members, due to the oil submergence at the inlet.
